UNITED STATES PATENT OFFICE.

JOHN H. DOWNER, OF COLTON, CALIFORNIA, ASSIGNOR OF ONE-FOURTH TO EDWIN H. VANDERMARK, OF COLTON, CALIFORNIA, AND ONE-FOURTH TO LUTHER L. YATES AND ONE-FOURTH TO ROBERT T. BURDETTE, BOTH OF LOS ANGELES, CALIFORNIA.

SADDLE FOR CAR RUNNING-BOARDS.

1,012,827.

Specification of Letters Patent. Patented Dec. 26, 1911.

Application filed November 28, 1910. Serial No. 594,422.

To all whom it may concern:

Be it known that I, JOHN H. DOWNER, a citizen of the United States, residing at Colton, county of San Bernardino, State of California, have invented new and useful Improvements in Saddles for Car Running-Boards, of which the following is a specification.

This invention relates to railroad cars and particularly to the construction and support of walks or roof platforms therefor, being similar to that described and claimed by me in an application filed Oct. 10, 1910, Serial No. 586,209.

15 The invention is particularly designed for use in connection with longitudinally disposed planks such as are commonly employed on the roofs of freight cars.

It is an object of the invention among other things to provide a saddle and means adjustably mounted thereon for holding the running boards of the walk or platform under tension.

It is a further object of the invention to provide clamping means upon the said saddle which are capable of engaging the boards in such a manner that they cannot slip or move longitudinally with respect to the saddle.

30 With these and other objects in view the invention consists in such novel constructions, combinations, and arrangements of parts as will be hereinafter fully described and claimed.

35 In the drawing forming a part of this specification. Figure 1 is a perspective view of a portion of a car roof showing the improved saddle mounted thereon. Fig. 2 is a longitudinal vertical sectional view taken 40 through the saddle and showing the planks gripped in position thereon. Fig. 3 is an end elevation of the saddle, the said saddle being removed from the car-roof. Fig. 4 is a detail perspective view of one of the 45 gripping jaws employed in connection with the saddle, the jaw shown in this view being an outside one. Fig. 5 is a similar detail perspective view of an intermediate jaw removed from the housing or boxing of the 50 saddle. Fig. 6 is a detail view showing the spring clamping plate in side elevation.

In the accompanying illustration I have shown the preferred form of my improved

saddle and will describe the same more particularly, reference being had thereto.

55

The saddle comprises a body portion 1 made to fit upon its under side upon the upper surface of the roof of the car to which it is applied and for this purpose it is usually inclined upwardly from the ends 60 toward the center as shown in Figs. 1 and 2 of the drawing. The said body portion 1 is generally made in the form of a hollow boxing or housing which is usually closed at one end as at 2 and the other end of the 65 said housing is made open as at 3. The housing is provided with inwardly extending flanges 4 and 5 at the top, extending approximately the entire length of the housing. The elongated slot 6 formed between 70 these flanges is adapted to receive movable plank gripping jaws as will be hereinafter described. At the closed end 2 of the housing the end wall is extended upwardly above the top of the housing a sufficient distance 75 to form a gripping jaw 7. Said fixed jaw 7 is provided with an inturned plank gripping edge 8 which is capable of embedding itself in the edge of the plank for holding it from becoming displaced. In order to prevent longitudinal movement of the plank with respect to the jaw, said jaw is also provided with projecting detents or teeth 80 as 9 which are also in position to embed themselves in the edge of the walk plank. One or more intermediate jaws as 10 are 85 employed and are movably mounted in place within the saddle housing 1. These intermediate jaws are preferably made so as to fit within the housing and are provided with recesses 11 upon their opposite edges which are adapted to fit and slide upon the flanges 4 and 5 of the housing. The heads or upper ends of said jaws are elongated sufficiently 90 to rest upon the upper surfaces of said flanges 4 and 5 as clearly indicated in Fig. 1. Near the upper edge of each of said jaws are formed laterally extending plank engaging edges as 12 there being preferably one of said gripping edges extending from 100 each face of the said intermediate jaw 10. These gripping edges 12 engage the planks of the car walk or floor in the same manner as the edge 8 heretofore described. The intermediate jaws 10 are also provided with 105 oppositely extending plank engaging points

or detents 13, there being preferably two of said points on each of the opposite faces of said intermediate jaws.

At the open end of the housing 1 a removable jaw 14 is employed which is generally made to closely fit the contour of the open end of said housing 1 as clearly indicated in Fig. 1 of the drawing. The upper edge of head 15 of the said removable end jaw is also provided with an inwardly extending gripping edge 16 and points or detents 17 for engaging the plank arranged against the said jaw. All of the jaws are provided with apertures in their body portions through which a securing rod or bolt 18 is passed for holding the jaws in such a position as to grip and firmly hold the planks that are interposed between them. The intermediate jaws are usually inserted 20 in position by turning them flat-wise with respect to the slot 6 of the housing until their head portions are brought down to the upper surface of the flanges 4 and 5. The said jaws are then turned transversely 25 with respect to the housing and the boards or planks 19 and 20 and 21 are placed in position between the said jaws as clearly shown in Fig. 2 and as indicated in dotted lines in Fig. 1. The movable mounting of 30 the intermediate jaws and of the end jaw 14 permits of the jaws being separated sufficiently to receive the planks between them, the plank 19 being forced against the fixed jaw 7. The jaws are then drawn together 35 against the edges of planks by means of the bolt 18 and the end nut 22 applied to the threaded portion thereof. Since there is always considerable expansion and contraction in the planking used in such walks 40 or floors it is found desirable to supply the saddle devices with means for accommodating the parts to their expansion and shrinkage. For this purpose a spring plate 23 is applied to the bolt 18 just inside of the 45 fixed head 24 of said bolt. The said spring 23 is preferably of the flat type bowed sufficiently to exert a constant pressure against the head 24 of the bolt 18. The said plate is perforated as at 25 so that it may be 50 slipped upon the bolt 18 before it is put into position.

It will be evident that when the bolt 18 is drawn up by the nut 22 and the jaws are forced tightly against the planks that the 55 spring 23 will be in position to exert a constant pressure against the head of the bolt 24 and tend to draw all of the movable jaws with planks between them toward the fixed jaw 7. By tightening the nut 22 sufficiently 60 to somewhat compress the spring 23, the said spring will be capable of taking up all shrinkage occurring in the planks and prevent any of the said planks or the movable jaws from becoming loose. The points 65 or detents 9, 13 and 17 are important in

that they are found very effective for preventing any longitudinal movement in the planks and also further assist in gripping the said planks in conjunction with the gripping edges 8, 12 and 16.

In order to facilitate the securing of the saddle in place upon the top or roof of a car the body portion thereof is formed with lateral projections 26 and 27 which are perforated and capable of receiving bolts which 75 are passed into the structure of the car. The saddles may then be firmly and readily secured to the roof of the car.

What I claim is:—

1. A saddle of the class described having 80 an elongated hollow body portion, movable plank gripping jaws capable of fitting into said body portion, and means for drawing them together to grip the planking.

2. A device of the class described comprising a hollow elongated housing open at one end and closed at the other, movable jaws capable of sliding into said body portion, and means for drawing them together to grip the planking.

3. A saddle comprising an elongated hollow housing, having a slot in its upper wall and provided with a fixed jaw at one end, a movable jaw mounted in the other end, intermediate jaws arranged within said 95 housing and a bolt passing through the housing and the said jaws for causing the jaws to clamp planking in position between them.

4. A saddle comprising an elongated hollow body portion closed at one end and having inturned flanges at its upper edges, movable jaws arranged to engage the slot between said flanges and having head portions adapted to rest thereon, plank gripping means projecting from the side faces of said jaws, and means for clamping the jaws against the planking.

5. A saddle of the class described comprising a body portion having fixed and 110 movable jaws, a bolt for holding the movable jaws in position, and means for exerting a spring pressure upon said bolt to accommodate the expansion and contraction in the parts.

6. A saddle of the class described comprising a body portion, and plank gripping jaws carried thereby and having gripping means projecting therefrom capable of preventing vertical and longitudinal movement 120 of the planks with respect to the parts of the saddle.

7. A saddle of the class described comprising a body portion carrying fixed and movable jaws, laterally extending gripping edges formed upon said jaws and laterally projecting points or detents also projecting from said jaws, and means for drawing the movable jaws against the plank.

8. A saddle of the class described com-

prising a housing formed with a fixed jaw, movable jaws mounted in said housing and tension controlled means for clamping said jaws against suitable planking.

5 9. A walk for a car roof comprising in combination with suitable planking, a transversely arranged saddle having a fixed jaw and movable jaws, a bolt for drawing the said jaws against the planking and a spring 10 plate arranged between the head of said bolt and the end of the housing for holding the parts together under tension.

10. A saddle having an elongated body with a fixed jaw at one end thereof, a movable jaw at the other end thereof, said jaws being adapted to engage the outside edges 15 of the planks forming a walk, intermediate jaws adapted to engage the adjacent edges of the planks forming the walk, and means 20 for adjusting said movable jaw.

11. A saddle of the class described comprising an elongated body having a fixed jaw at one end thereof, a movable jaw at the other end, intermediate jaws engaging said 25 body retained thereby and disposed between the adjacent edges of the planks, and means for advancing said movable jaw to clamp the planks.

12. A walk for a car roof comprising in 30 combination, a transversely disposed saddle

having jaws near the ends thereof, planks laid on said saddle, the outer edges of said planks engaging said jaws and retained thereby, intermediate jaws disposed between the adjacent edges of said planks, and means 35 for moving said jaws to clamp said planks therebetween.

13. A running board saddle, comprising a main body or casting having a supporting flange, and a laterally adjustable clamp for 40 engaging the outside edge of a board.

14. A running board saddle having a body portion, and end clamp jaws for the outside edges of the boards, the jaws having a positive connection with the body for preventing 45 vertical movement of the jaws.

15. A running board saddle, comprising a main body or casting having a flange for supporting a board, an integral clip for engaging one edge of the board and a laterally adjustable clamp for engaging the other edge 50 of the board.

In witness that I claim the foregoing I have hereunto subscribed my name this 21st day of November, 1910.

JOHN H. DOWNER.
